UNITED STATES PATENT OFFICE.

EVERARD RICHARD CALTHROP, OF LONDON, ENGLAND.

2,157

BALLOON.

1,302,007.

Specification of Letters Patent. Patented Apr. 29, 1919.

Application filed September 21, 1915. Serial No. 51,873.

To all whom it may concern:

Be it known that I, EVERARD RICHARD CALTHROP, a subject of the King of Great Britain, residing at London, in the county of 5 Middlesex, England, have invented new and useful Improvements Relating to Balloons, of which the following is a specification.

My invention has reference to balloons and is particularly applicable to captive balloons such as are employed for military 10 signaling reconnaissance or observation purposes.

The chief difficulties experienced in the use of captive balloons as commonly employed arises from the tendency of the balloon or its cable to spin while even a moderate gale of wind renders them useless for all practical purposes for the reason that the balloon and its car is liable to assume such 20 an inclination that apart from the imminent danger of the aeronaut being precipitated from the car the constant spinning and swaying of the balloon prevents or is very detrimental to accurate observations being 25 taken.

To obviate this defect various expedients have been suggested with the object of insuring that the car of the balloon shall hang vertically when due to the pressure of the 30 wind the gas bag assumes an angular position but so far as I am aware these suggested arrangements have been either too complicated or cumbersome to admit of their employment in actual practice or have been 35 of a wholly impracticable nature.

A system of cordage attached to the holding cable, the balloon and the car has also been adopted in order to maintain the gas bag and the car in a vertical position but 40 such an arrangement has developed a further difficulty namely that of "kiting" of the balloon which is a source of great inconvenience to the aeronaut.

Now the primary object of my present invention is to provide improvements in balloons of the above mentioned type whereby the aforementioned disadvantages may be overcome to the end of obtaining a simple and reliable construction which shall insure 45 that no matter what position the gas bag may assume the car shall always be maintained in a vertical position.

A further object is to provide means whereby any spinning motion of the balloon 50 or the holding cable shall be prevented from being communicated to the car.

A further object of my invention is to provide means whereby the point at which the pull of the holding cable is exerted may be readily altered or adjusted by the occupant 60 of the car to meet the varying stresses of air current likely to be encountered during an ascent.

An important advantage resulting from my improved arrangement is that the aforementioned "kiting" action is absolutely prevented.

With these ends in view my invention in its broadest aspect may be said to be embodied in a construction in which the car is connected to the balloon by a universal suspension means being also provided whereby the pull of the holding cable may be exerted at a point between the balloon and the car.

The hereinbefore mentioned objects and 75 such others as may be incidental thereto are attained by the means which I will now proceed to describe in detail for the ready comprehension of which reference should be had to the accompanying drawings in which:

Figure 1 represents a perspective view of one form of my invention.

Fig. 2 is a sectional view of a ball thrust and journal bearing positioned between the balloon and the car and hereinafter more 85 particularly referred to.

Fig. 3 is a perspective view of a modified arrangement and

Fig. 4 illustrates a further modification.

Fig. 5 is a sectional view of a universal 90 joint which may be employed in connection with my improved arrangement and

Fig. 6 is a detail view hereinafter more particularly described.

In that embodiment of the invention illustrated in Fig. 1 the suspension cords 1 of the balloon are attached to the usual hoop 2 which latter is connected by the stays 3 with a rotatable anti-friction bearing 4 forming part of a universal suspension of which the 100 pivotal joint 5 also forms a member. Said joint 5 is attached to a bar or yoke piece 6 from which the car 7 is suspended such as by cords or the like 8. Such a suspensory arrangement forms a universal joint between 105 the hoop of the balloon and the car as the cords 8 are passed loosely around the bar 6 so that the car may swing thereon and it should here be remarked that the term "universal joint" employed throughout this specification and the claiming clauses is intended 110 to define an arrangement of parts which will

permit of rotary as well as angular motion in contradistinction to what is popularly known as a "universal" joint which usually permits only of angular motion in two planes situated at right angles to each other.

Loosely attached to each end of the bar 6 are cords or the like 9 the opposite ends of which are loosely attached to a second bar or yoke piece 10 to which the holding cable 11 is secured by means of the ball swivel connection 12 whereby any twisting of the cable 11 will be prevented from being communicated to the car and balloon.

The construction of the rotatable bearing 4 will be seen from an inspection of Fig. 2. It comprises a spindle 13 which is preferably tubular to accommodate the passage of the cord or cords 14 for operating the valve or valves of the balloon. The spindle 13 is positively connected at its lower end to the aforesaid joint 5 and is surrounded by a sleeve 4' rotatably mounted thereon by means of the ball bearings 15, 16 and 17. Sockets 18 are provided upon the sleeve 14 whereby the ends of the stays 3 are secured thereto.

By means of the arrangement hereinbefore described any spinning motion of the balloon will be taken up by the rotatable bearing 4 while the universal suspension 30 hereinbefore described will allow of the gas bag being deflected to any angle without affecting the vertical position of the car 7 as the pull of the holding cable is exerted in line with the universal joint and the car 35 will therefore swing between the bars 6 and 10 and their connecting cords 9.

It may in some cases be desirable that the point at which the resultant forces of the inflated balloon and the pull on the holding 40 cable act should be capable of adjustment in order to counteract any uneven distribution of weight in the car or to prevent abnormal swinging or rocking thereof and to this end the arrangement illustrated in Fig. 45 3 or Fig. 4 may be adopted.

In Fig. 3 the universal joint 5 is attached to the member 19 in the ends of which the bars or yoke pieces 6' are journaled. The inner end of each of said bars 6' carries a toothed wheel meshing with a worm 20 adapted to be rotated by the handle 21 while the opposite end of each of said bars is provided with a lever 22 to which the cords 9 connected to the lower bar 10 are respectively attached. Such a construction enables the occupant of the car to raise or lower the position of the point at which the pull of the holding cable is exerted by operating the handles 21 thereby rotating the 60 bars 6' and the levers 22.

In the arrangement illustrated in Figs. 1 and 3 it will be seen that the bar or yoke 6 or 6' forms part of what may be termed the balloon frame but as an alternative arrangement the bar 6 may form part of the

car frame. Such a construction is illustrated in Fig. 4 wherein the bar 6 is journaled in bearings 23 supported in brackets 24 rigidly attached to the hoop 25 of the car. One or both of said brackets 24 is provided with a worm 20 engaging a toothed wheel 26 keyed to the bar 6 whereby this latter and with it the levers 22 may be rotated in the manner described with reference to Fig. 3 and for a like purpose.

The universal joint hereinafter referred to is shown more or less diagrammatically as any appropriate kind may be used but in Fig. 5 I have illustrated a joint which may be advantageously employed in connection 80 with my invention in place of the joint 5 and rotatable anti-friction bearing 4 above described.

In this arrangement the hollow spindle 13 is connected to the bar 6 such as by the stays 85 27 and carries at its upper end a hemispherical cup 28 which is embraced by the rings 29 and 30 in which ball races are formed for the reception of the balls 31. To the ring 30 another ring 32 is bolted said ring serving for the attachment of the stays 33 which are connected to hoop 2 of the balloon. The spindle 13 may be provided with a buffer 34 of rubber or other resilient material against which the ring 32 may abut when 95 said ring reaches its limit of angularity as shown in Fig. 5 or the alternative arrangement shown on the left of this figure may be adopted wherein a vertically disposed antifriction roller 35 is illustrated.

A universal joint constructed in this manner not only allows any spinning motion of the balloon or the car to be compensated for but also takes up the thrust that may be exerted by the balloon through the ring 32 105 onto the ball bearings 31.

It is of course desirable that the connection between the balloon and the yoke piece or bar 6 should possess maximum strength with a minimum weight consistent with 110 safety and my invention therefore contemplates the arrangement illustrated in Fig. 6 wherein I have shown the rotatable bearing 4 as being provided with angularly disposed annular flanges 36 and 37. A cone 38 115 preferably of a light metal such as duralumin is bolted to the flange 36 the cordage 1 of the balloon being attached thereon as shown. A second preferably metal cone 39 is bolted or otherwise secured to the flange 37 of the member 4 and to the cone 38. By 120 this means a light and rigid structure is formed possessing great strength and lightness.

The aforesaid yoke to which the cable is 125 attached may advantageously be employed to support the aerials of a wireless signaling apparatus.

While I have described in the foregoing specification the preferred construction of 130

parts and the operation thereof it is to be understood that numerous changes of construction may be made without departing from the spirit and scope of my invention 5 and I therefore do not wish to be understood as limiting myself by the positive terms employed in connection with the description excepting such as the state of the art may require.

10. What I claim is:

1. The combination with a captive balloon and a car therefor of a universal suspension member between said balloon and car a bar rotatably associated with said universal 15 suspension member arms at each end of said bar, a bar normally positioned beneath said car, a holding cable rotatably secured to said bar means for connecting said last mentioned bar with the arms carried by the 20 first mentioned bar and means for rotating said bar.
2. The combination with a captive balloon and a car therefor, a universal suspension member between said balloon and car, a rotatable antifriction thrust and journal bearing associated with said universal suspension member, upper and lower bars or yoke pieces, means for connecting said bars or 25

yoke pieces, and a holding cable rotatably attached to the lower of said bars.

3. The combination with a captive balloon and a car therefor, a universal suspension member between said balloon and car, a rotatable antifriction thrust and journal bearing associated with said universal suspension 35 member, upper and lower bars or yoke pieces, arms carried by the upper bar or yoke piece, means for connecting said arms with the lower bar or yoke piece, means for rotating said upper bar, and a holding cable 40 rotatably attached to said lower bar or yoke piece.

4. The combination with a captive balloon and a car therefor of a rotatable antifriction thrust and journal bearing, a conical member 45 secured to the upper part of said bearing, a second conical member secured to the lower part of said bearing and to the first mentioned cone and adapted for engagement with the rigging of the balloon, 50 a bar or yoke piece associated with said bearing by means of a universal joint, and means for attaching a holding cable to said bar or yoke piece.

Dated this 6th day of September, 1915.

EVERARD RICHARD CALTHROP.
